UNITED STATES PATENT OFFICE.

WILLIAM H. MURSCH, OF WARREN, PENNSYLVANIA.

SPEED-REGULATING GOVERNOR.

1,001,065.

Specification of Letters Patent. Patented Aug. 22, 1911.

Application filed October 27, 1910. Serial No. 589,299.

To all whom it may concern:

Be it known that I, WILLIAM H. MURSCH, citizen of the United States, residing at Warren, in the county of Warren and State 5 of Pennsylvania, have invented certain new and useful Improvements in Speed-Regulating Governors, of which the following is a specification.

My invention relates to speed governors, 10 and has especial reference to devices adapted to automatically control the throttle valve of an engine by means of centrifugal force.

The chief objects of the improvements which constitute the subject matter of this 15 application for patent are:—to provide a simple and effective apparatus for regulating the speed of an engine or other machine; to furnish a speed governing device that will be sensitive to comparatively slight variations in the rate of movement of the connected mechanism, and to produce a device that will have few parts, and that will not be likely to get out of order.

I accomplish the desired results by employing the apparatus illustrated in the accompanying drawing, which forms a part of this application, the details of construction being disclosed in the following views:

Figure 1 is a vertical section median section of the complete apparatus, and Fig. 2 is a top plan view, with the cover of the rotary receptacle removed.

Referring to the details of the drawing, the numeral 5 indicates a suitable hollow 30 pan or receptacle in the form of a drum arranged horizontally and provided with a central hub or sleeve 6 through which passes a vertical operating shaft 7, to which the receptacle or drum is keyed. The upper side 35 of the said drum is closed by a removable circular plate 8, which forms a cover for the receptacle, and is secured to the sides 9 of the drum by suitable bolts or screws 10, which engage holes 11 in the rim. This 40 cover is provided with a circular central aperture 12 through which the said hub 6 and shaft 7 project. Arranged within the drum is a resistance or friction wheel comprising a rim 13, and a hub 14, connected 45 by arms 15. The hub 14 surrounds the hub or sleeve 6 of the drum and has a turning fit therewith. The lower end of the hub 14 rests upon the bottom of the drum, as indicated at 16, and has a bearing at this point. 50 The diameter of this friction or resistance wheel is a little less than that of the sur-

rounding drum, and its rim is narrower than the height of the surrounding wall 9, and is supported so that it does not touch the bottom or top of the receptacle, the only 55 bearing being at the hub as above described. The central opening 12 of the cover is of sufficient diameter to allow the upper end of the hub 14 to project beyond the cover and to this projecting end are attached two diametrically arranged arms 17, 18, secured to the said hub by bolts or screws 19. The lever 17 is yieldingly connected by a coiled spring 20, to a convenient fixed support (not shown), so that the friction wheel 13 is held 60 from rotating with the receptacle or drum when the latter is revolved, having simply an oscillating movement caused by variations in the frictional resistance applied to the said wheel, and limited by the force of 65 the coiled spring 20. Variations in the resistance offered to the wheel 13 are brought about by the action of a suitable liquid 21, with which the pan is partially filled. When 70 the said drum or pan 5 is revolved by turning the shaft 7 by suitable gearing (not shown) the centrifugal force will throw the liquid toward the periphery and this accumulation of the fluid about the rim of the wheel will cause an increased pull upon the 75 spring 20, which will correspondingly yield moving the lever 18 which has pivoted to the extremity a link 22 which extends to the throttle valve or other speed controller, the 80 said valve not being shown since it forms no 85 part of this invention.

Water, oil or other liquid may be employed for the friction producing median, but I prefer to use under certain circumstances non-freezing substance such as glycerin, which will not materially thicken at 90 low temperature. A certain amount of resistance will be offered to the liquid by the arms of the wheel 13, and to further increase the resistance I pierce the rim with one or 95 more of holes 23, which may be made as numerous as is found desirable.

Having thus described my invention, what I claim as new, is:—

In a centrifugal governor, the combination of a vertical shaft, a hollow cylinder mounted upon said shaft, said cylinder having one end closed and the opposite end open, a plate forming a cover for the open end, said cover being removably secured to 105 the peripheral wall of the cylinder, and having a concentric aperture therethrough, a 110

hub formed integral with the cylinder and extending through the aperture in the cover, said hub having a central bore to receive the said vertical shaft, a resistance wheel arranged horizontally within said cylinder, a hub for the wheel adapted to turn upon the hub of the cylinder and having its upper end projecting through the aperture in the cover, the rim of said wheel having apertures extending radially therethrough, a pair of arms attached to the hub of the resistance wheel externally of the cylinder and

projecting radially, a spiral spring having one end secured to one of said arms, and a link pivoted to the opposite arm and adapted to be attached to the device to be regulated. 15

In testimony whereof I affix my signature in the presence of two witnesses.

WILLIAM H. MURSCH.
